NEEDLEWORK FRAME

Clifford W. Morse, Normandy, Mo.

Application December 24, 1947, Serial No. 793,703

8 Claims. (Cl. 45—24)

1

This invention relates in general to needlework frames used in the making of needlepoint, embroidery, and similar hand work.

The primary object of this invention is to provide a convenient, lightweight, and easily handled frame for supporting fabrics in tightly drawn position during the application thereto of various types of embroidery work, such as needlepoint, and the like.

It is a further object of the present invention to provide a frame of the type stated which is rugged and durable and may be conveniently carried from place to place by the user and may be set up on a table, rested across the arms of a chair, or disposed in any other suitable or convenient position as may suit the needs or requirements of the user.

It is an additional object of the present invention to provide a frame of the type stated in which the work may be progressively moved across the stitching area without making it necessary to dismantle the frame or otherwise rearrange the fabric which is held thereon.

It is also an object of the present invention to provide a frame which will hold a piece of fabric while it is being embroidered without undue stretching or distortion of the fabric or of the decorative stitches, such as needlepoint or embroidery.

It is a further object of the present invention to provide a frame of the type stated having means for applying any desired amount of tension to the fabric which is mounted and supported thereon.

It is also an object of the present invention to provide a needlework frame adapted for making embroidery, needlework, and the like having a working surface which facilitates movement of the user's needle.

With the above and other objects in view, my invention resides in the novel features of form, construction, and combination of parts presently described and pointed out in the claims.

In the accompanying drawing:

Figure 1 is a perspective view of the needlework frame constructed in accordance with and embodying the present invention and showing a piece of fabric in position on said frame for being embroidered;

Figure 2 is a perspective view of the needlework frame with the aprons removed;

Figure 3 is an end elevational view of the needlework frame;

Figure 4 is a transverse sectional view taken along line 4—4 of Figure 2.

2

Referring now in more detail, and by reference characters to the drawing, which illustrates a preferred embodiment of the present invention, A designates a needlework frame constructed preferably of wood or plastic and comprising end members 1, 1', of somewhat inverted T-shape having a base portion 2 and an upwardly extending central leg portion 3. Secured to the outer faces of the end members 1, 1', and along the vertical center line of the leg portion, are upstanding support members 4, 4', extending beyond the upper margin of the end members 1, 1'. Mounted rigidly at their opposite ends in, and extending lengthwise between, the base portions 2 of the end members 1, 1', are stationary parallel rods 5. Similarly, extending between, and secured to, the upper ends of the support members a, is a relatively wide transverse bar 6 engaged along its downwardly presented margin with the top surface of the leg portions 3. Secured upon the upper margin of the transverse bar 6 is a half-round, curved metallic strip or bead 7, the surface of which is flush with the upper margin of the support members a. Rotatably mounted at their upper ends in, and extending between, the base portions 2 of the end members 1, 1', are horizontal rollers 8, 8', somewhat larger in diametral size than, and having their longitudinal axes in substantially the same plane as, the rods 5.

Adjacent the end member 1, and inwardly thereof, is a relatively narrow plate member 10 seated upon the rods 5 and being provided centrally with an aperture 11. Extending downwardly through the aperture 11 is a bolt 12, the lower end of which projects through an aligned aperture 13 in a transversely extending brake bar 14 loosely supported from the rods 5 by means of screws 15. Upon its downwardly projecting end, the bolt 12 is provided with a wing nut 16. The brake bar 14 is parallel to, and substantially longer than, the plate member 10, and is disposed at its ends beneath the rollers 8, 8'. Suitably secured to the upper surface of the brake bar 14, for braking or clamping engagement with the rollers 8, 8', are friction pads 17, 17', fabricated preferably of rubber or other similar material.

Tacked, or otherwise suitably mounted, upon the rollers 8, 8', are so-called aprons 18, 18', respectively, formed of a suitable length of tightly woven, and substantially non-stretchable fabric. The aprons 18, 18', are wrapped around their respective rollers 8, 8', and are free at their outer ends so as to extend inwardly beneath the rods

5 and upwardly toward the transverse bar 6 for stitched securement to the piece of fabric being worked upon, substantially in the manner shown in Figure 1.

In use, the wing nut 16 is loosened, dropping the brake bar 14 and its associated friction pads 17, 17', downwardly out of contact with the rollers 8, 8'. A section of fabric *f*, upon which the needlework is to be done, is hung loosely over the bead 7 of the bar 6 and then stitched, pinned, or otherwise suitably secured at its opposite ends, respectively, to the free ends of the aprons 18, 18'. The rollers 8, 8', are then manually rotated, rolling the aprons 18, 18', up and drawing the fabric *f* tightly over the bar 6. More or less of the one apron 18 may be rolled up on its roller so that a very narrow area of the fabric *f* on which it is desired to do the needlework will be drawn tightly over the bead 7, all as best seen in Figure 1. If the fabric section *f* is very long, a portion of it will be rolled up around one or the other of the rollers 8, 8', or, for that matter, portions of it may be rolled up around both of the rollers 8, 8'. It will thus be seen that the frame A is capable of accommodating a relatively wide range of different fabric widths and lengths.

When the fabric section *f* is properly positioned upon the frame A, the wing nut 16 is tightened drawing the brake bar 14 and its associated friction pads 17, 17', up into snug engagement with the rollers 8, 8', respectively. Any desired amount of tension may be applied, although ordinarily just enough tension will be applied to hold the rollers stationary against the normal pull of the fabric so that the fabric will be held in reasonably tight position without undue stretching of the fibers. Actually, the rollers 8, 8', may be manually rolled in opposite directions, drawing the fabric as tight as the user desires, and the wing nut 16 tightened down so as to hold the rollers 8, 8', in substantially immobile or non-rotatable condition.

The user then works the line of needlepoint so positioned over the bead 7, which, by its smoothness and curvature, provides an easy sliding surface for the user's needle as it projects through the material. At the completion of the particular line of the needlepoint, the friction pads 17, 17' may be sufficiently removed from contact with the rollers 8, 8', by manipulation of the wing nut 16 to permit the user to turn the rollers 8, 8', in order to bring another line into position for working. The parallel rods 5 aid in maintaining the tautness of the material when in position for working and additionally prevent undue slack when the rollers 8, 8', are freed for rotation. By the use of the aprons 18, 18', the marginal portions of the fabric *f* may be positioned tautly over the transverse bar 6 and rendered accessible.

It will be noted that the portion of the fabric being worked upon is bent over the arcuate top of the bar 6 so that a relatively narrow area is presented upwardly along the center of the arc of the bead 7 for actual application of the stitches. By reason of the fact that the material extends downwardly and away from this narrow working line on both sides, the interstices of the fabric will be opened slightly to facilitate the penetration of the needle without imposing and unnecessary stretching forces upon the fibers of the fabric and, furthermore, the needle may be pushed through the fabric in a more or less horizontal direction, thereby materially facilitating the insertion of stitches into the fabric and accelerating the rate at which the user may make the needle-

point or other similar embroidery stitches being applied to the fabric. In this same connection, it should be noted that the hardened arcuate surface of the bead 7 guides the point of the needle through the fabric in a uniquely convenient manner particularly suitable to the making of needle-point and eliminates the inconvenience of pushing the needle vertically through the fabric and then reaching underneath the fabric to push the needle back up vertically in the reverse direction, as has heretofore been the practice in this type of needlework.

It should be understood that changes and modifications in the form, construction, arrangement, and combination of the several parts of the needlework frame may be made and substituted for those herein shown and described without departing from the nature and principle of my invention.

Having thus described my invention, what I claim and desire to secure by Letters Patent is:

1. A needlework frame comprising spaced parallel end members each having a relatively wide horizontal base portion and a centrally disposed upwardly extending leg, a transverse bar rigidly mounted at its ends upon and extending horizontally between the upper ends of said legs, the upwardly presented face of said bar providing a working surface, a pair of spaced parallel rods mounted at their ends in and extending between the base portions approximately beneath the bar, a pair of rollers operatively mounted at their ends in and extending between the base portions, said rollers being respectively disposed in outwardly spaced relation to and on opposite sides of the rods, and means for securing to the rollers the ends of a length of fabric upon which the needlework is to be performed in such a manner that the fabric will extend from one roller inwardly under one rod thence upwardly over the bar and downwardly beneath the other rod and thence outwardly to the other roller.

2. A needlework frame comprising spaced parallel end members each having a relatively wide horizontal base portion and a centrally disposed upwardly extending leg, a transverse bar rigidly mounted at its ends upon and extending horizontally between the upper ends of said legs, the upwardly presented face of said bar being arcuate for providing a working surface over which the user's needle will easily slide during embroidery and the like of the work thereon supported, a pair of spaced parallel rods mounted at their ends in and extending between the base portions approximately beneath the bar, a pair of rollers operatively mounted at their ends in and extending between the base portions, said rollers being respectively disposed in outwardly spaced relation to and on opposite sides of the rods, means for securing to the rollers the ends of a length of fabric upon which the needlework is to be performed in such a manner that the fabric will extend from one roller inwardly under one rod thence upwardly over the bar and downwardly beneath the other rod and thence outwardly to the other roller, and braking means mounted on the frame for operative engagement with said rollers.

3. A needlework frame comprising spaced parallel end members each having a relatively wide horizontal base portion and a centrally disposed upwardly extending leg, a transverse bar rigidly mounted at its ends upon and extending horizontally between the upper ends of said legs, a pair of spaced parallel rods mounted at their ends

in and extending between the base portions approximately beneath the bar, a pair of rollers operatively mounted at their ends in and extending between the base portions, said rollers being respectively disposed in outwardly spaced relation to and on opposite sides of the rods, means for securing to the rollers the ends of a length of fabric upon which the needlework is to be performed in such a manner that the fabric will extend from one roller inwardly under one rod thence upwardly over the bar and downwardly beneath the other rod and thence outwardly to the other roller, a flexible bar shiftably mounted upon and depending from said rods and extending laterally outwardly on opposite sides thereof having its ends disposed beneath the rollers, friction pads mounted on the ends of said bar for braking engagement with the rollers, and means for adjustably urging the bar upwardly for optionally increasing and decreasing the degree of frictional pressure applied to the rollers by the friction pads.

4. A needlework frame comprising spaced parallel end members each having a relatively wide horizontal base portion and a centrally disposed upwardly extending leg, a transverse bar rigidly mounted at its ends upon and extending horizontally between the upper ends of said legs, said bar being provided upon its upper longitudinal margin with an upwardly presented arcuate metallic bead for providing a working surface over which the user's needle will easily slide during embroidery and the like of the work thereon supported, a pair of spaced parallel rods mounted at their ends in and extending between the base portions approximately beneath the bar, a pair of rollers operatively mounted at their ends in and extending between the base portions, said rollers being respectively disposed in outwardly spaced relation to and on opposite sides of the rods, and means for securing to the rollers the ends of a length of fabric upon which the needlework is to be performed in such a manner that the fabric will extend from one roller inwardly under one rod thence upwardly over the bar and downwardly beneath the other rod and thence outwardly to the other roller.

5. A needlework frame comprising spaced parallel end members each having a centrally disposed upwardly extending leg, a transverse bar rigidly mounted at its ends upon and extending horizontally between the upper ends of said legs, the upwardly presented face of said bar being arcuate for providing a working surface over which the user's needle will easily slide during embroidery and the like of the work thereon supported, a pair of spaced parallel rods mounted at their ends in and extending between the lower portions of the end members approximately beneath the bar, a pair of rollers operatively mounted at their ends in and extending between the lower portions of the end members, said rollers being respectively disposed in outwardly spaced relation to and on opposite sides of the rods, and means for securing to the rollers the ends of a length of fabric upon which the needlework is to be performed in such a manner that the fabric will extend from one roller inwardly under one rod thence upwardly over the bar and downwardly beneath the other rod and thence outwardly to the other roller.

6. A needlework frame comprising spaced parallel end members each having a relatively wide horizontal base portion and a centrally disposed upwardly extending leg, a transverse bar

rigidly mounted at its ends upon and extending horizontally between the upper ends of said legs, a pair of spaced parallel rods mounted at their ends in and extending between the base portions approximately beneath the bar, a pair of rollers operatively mounted at their ends in and extending between the base portions, said rollers being respectively disposed in outwardly spaced relation to and on opposite sides of the rods, a flexible bar shiftably mounted upon and depending from said rods and extending laterally outwardly on opposite sides thereof having its ends disposed beneath the rollers, friction pads mounted on the ends of said bar for braking engagement with the rollers, and means for adjustably urging the bar upwardly for optionally increasing and decreasing the degree of frictional pressure applied to the rollers by the friction pads.

7. A needlework frame comprising spaced parallel end members each having a relatively wide horizontal base portion and a centrally disposed upwardly extending leg, a transverse bar rigidly mounted at its ends upon and extending horizontally between the upper ends of said legs, a pair of spaced parallel rods mounted at their ends in and extending between the base portions approximately beneath the bar, a pair of rollers operatively mounted at their ends in and extending between the base portions, said rollers being respectively disposed in outwardly spaced relation to and on opposite sides of the rods, a flexible bar shiftably mounted upon and depending from said rods and extending laterally outwardly on opposite sides thereof having its ends disposed beneath the rollers for braking engagement with the rollers, and means for adjustably urging the bar upwardly for optionally increasing and decreasing the degree of frictional pressure applied to the rollers by the rods.

8. A needlework frame comprising spaced parallel end members each having a relatively wide horizontal base portion and a centrally disposed upwardly extending leg, a transverse bar rigidly mounted at its ends upon and extending horizontally between the upper ends of said legs, a pair of spaced parallel rods mounted at their ends in and extending between the base portions approximately beneath the bar, a pair of rollers operatively mounted at their ends in and extending between the base portions, said rollers being respectively disposed in outwardly spaced relation to and on opposite sides of the rods, a bar shiftably mounted upon said rods and extending laterally outwardly on opposite sides thereof having its ends disposed adjacent the rollers for braking engagement therewith, and means for adjustably urging the bar upwardly for optionally increasing and decreasing the degree of frictional pressure applied to the rollers by the rods.
